UNITED STATES PATENT OFFICE.

PERRY BROWN, OF WILMINGTON, DELAWARE.

CAR-COUPLING.

No. 898,961.

Specification of Letters Patent. Patented Sept. 15, 1908.

Application filed October 27, 1903. Serial No. 178,726.

To all whom it may concern:

Be it known that I, PERRY BROWN, a citizen of the United States of America, and resident of Wilmington, in the county of Newcastle, in the State of Delaware, have invented certain new and useful Improvements in Car-Couplers, of which the following is a specification.

This invention relates to an improvement 10 in that class of car couplers known as twin jaw couplers and the principal object of my invention is to provide a coupler of that class in which the locking pin is vertically operated and is moved from its under side.

15 Another object is to provide a coupler of this form in which the upper part of the locking pin is entirely inclosed within a housing so that it is free from accumulation of dirt, ice or any other obstruction.

20 With these principal objects in view, my invention consists in the peculiar construction, arrangement and combinations of parts hereinafter more particularly described and then definitely claimed.

25 In the drawings accompanying and forming part of this application: Figure 1 represents a side elevation, with most of the parts in vertical section, of a coupler made in accordance with the preferred embodiment of 30 my invention, the section, so far as the device for operating the locking pin is concerned, being taken through the line *a—a* of Fig. 3; Fig. 2 is a top plan view of the same with the coupling head in section; Fig. 3 is a 35 detail, in section, of the rock shaft and connected parts for operating the locking pin; Fig. 4 represents, in perspective, the locking pin, detached; Fig. 5 is a perspective view of the pivoted dog or "lock-set" for holding 40 the locking pin in its unlocked position; Fig. 6 is a side elevation of a modified form of my coupler, with most of the parts in vertical section; Fig. 7 is a similar view of the same with the locking pin in the opposite position 45 from that shown in Fig. 6; Fig. 8 is a perspective view of the locking pin, detached; Fig. 9 is a perspective view of the pivoted dog or "lock-set", also detached.

Referring now to the details of the drawings by numerals, and especially to Figs. 1 to 5, the numeral 1 designates a coupling head which may be of any desired construction and which is provided with the usual or any desired form of knuckle 2 which is pivoted 55 to swing on the pin 3 as in many forms now

in use. This knuckle is of course provided with a tail 4 which swings within the interior of the coupling head and is locked therein by a pin 11. The only novel features about these parts is the wearing-plate 50 5 of the coupling knuckle 3 which is formed of chilled or hardened metal so as to best withstand the wear and has two lugs 6 shown in dotted lines in Fig. 1 (and also in full lines in Fig. 6) which project into recesses formed 55 in the recessed face of the knuckle; the lugs 6 coacting with the upper part 7 and the lower part 8 of the interior of the knuckle, so that the wearing plate is absolutely prevented from having any vertical movement. 70 . Rivets or other means 9 are provided by which the wearing-plate is secured in its recess in the face of the knuckle. (See also Figs. 6 and 7 for sectional views of this wearing-plate and its lugs.)

75 Near the center of the coupler is formed a vertical recess or passage 10 for the locking pin 11, which recess and pin are preferably formed rectangular in shape, and in the form shown in Fig. 1 the vertical recess is formed 80 of a housing 12 which is closed at its top and open at its bottom, and also has an open space 13 at its central portion through which passes the tail 4 of the knuckle 2 as said tail is swung open or closed. This opening 13 is 85 also in communication with the opening 14 in the shank 15 of the coupler so as to permit a dog or "lock-set" 16, pivoted in the shank, to swing through the opening 13 as will be explained. The shank of the coupler is also 90 provided with one novel feature: a bracket or stop 15^a which is cast integral with the shank 15 so that it projects into the path of the end sill shown in Fig. 1. This is for the purpose of preventing injury to the springs 95 when they have been drawn to their full capacity.

100 The locking pin 11 is preferably of the peculiar shape shown in Fig. 4, and is provided with a central opening 20 in its upper end in which is situated one end of a coiled spring 21, the other end of which spring bears on the under surface of the top of the housing 12 so as to normally keep the pin in its lowermost position, to which it would naturally fall by gravity, but which might tend to "creep" upward were it not for the action of the spring. The locking pin 11 is also formed with a deep recess 24 through which, when 105 the pin 11 is held in its elevated position, the 110

tail 4 of the knuckle 2 may pass in opening and closing, as said recess is directly in the path of said tail 4 when the pin is elevated. In order to hold said pin elevated when desired, I employ the hereinbefore mentioned dog or lock-set 16, which is preferably formed with trunnions 27 by which the dog is pivoted in grooves formed in lugs 28 cast in the bottom of the shank. The upper end of this 10 dog or lock-set 16 is adapted to drop against the vertically moving pin 11 and the pin is formed with a recess 30 which, when the pin is elevated, comes opposite the upper end of the dog 16 when the said end falls in said recess 30 and holds the pin elevated, in a manner which will be well understood by those skilled in this art. While this pin looks weak in its center, it will be seen that the upper part, which has to withstand the load, is a 15 solid rectangular block except for the opening 20. Therefore this pin is lightest where no strength is needed, and is of enormous resisting power where the maximum amount of strength is needed.

25 It will be obvious that any means may be used to give the coupling pin 11 a vertical movement to unlock the coupler when this action is necessary, but I prefer the novel arrangement shown in my drawings, and which 30 comprises a rock-shaft 35 which is journaled in a bearing 36 formed integral with the coupling head. One end of this rock-shaft is formed with a crank arm 37, the end of which is bent to form a wrist pin 38 which 35 projects into a groove or channel 39 formed in the lower end of the locking pin 11, as clearly shown in Fig. 1. It follows from this that when the rock-shaft 35 is rocked in one direction, the crank arm 37 is swung so as to 40 move the wrist pin 38 on an arc of which the axis of the rock-shaft 35 is the center, and this movement of the wrist pin will cause the pin to be projected upwardly in its housing 12, as will be evident from an inspection of 45 my drawings. In order to prevent the locking pin 11 from dropping too far, the end of the bearing 36 is provided with a projecting portion 40 against which the crank arm 37 abuts when the locking pin is at its extreme 50 lower position. The opposite end of the rock-shaft 35 is provided with a preferably rectangular end 41 and to this end is secured, by means of a pin 42 or otherwise, a sleeve 43 in the end of which is an opening 44 through 55 which projects a bent arm 45 of an operating shaft 46 whose other and free end is formed with a handle 47 by which the whole mechanism may be operated. It will be manifest that any movement given by an operator or 60 attendant to the crank handle 47 will be imparted to the sleeve and from it to the rock-shaft 35 from which it is transmitted to the locking pin to raise or lower the same when necessary. In order that this operating 65 mechanism may be held in the normal position

shown in Fig. 1 with the locking pin in its locked position, I employ a coiled spring 50, one end of which fits in a recess in the sleeve 43 and the other in the bearing 36, as clearly seen in Fig. 3.

The operation of my coupler has been almost fully described in giving the detailed description of its various parts; yet it may be well to state that when the parts are in the position shown in Fig. 1, and it is desired to 70 "uncouple", all that it is necessary for the attendant to do is to grasp and turn the handle 47, which of course rocks the rock-shaft 35, and swings the crank arm 37 so that its wrist pin 38 also swings and elevates the pin 80 against the tension of the spring 21. The knuckle may now be withdrawn, and as its tail 4 swings past the dog or lock-set 16, the upper end of the latter drops into the recess 30 and thus holds the locking pin elevated. 85 When the cars are to be coupled, the pin of course being held up by its dog or lock-set 16, the tail of the knuckle passes through the large opening 24 of the locking pin and in passing through it, said tail swings against 90 the dog or lock-set and pushes it back to the position shown in Fig. 1; at this point the locking pin will drop until it rests upon the tail of the knuckle, and further movement of the knuckle will swing its tail completely 95 within the coupling head to the position shown in Fig. 1, when the locking pin may drop into the locking position. If it becomes necessary when the pin is held elevated by the lock-set 16, to permit the locking pin to drop, it is only necessary to move the projecting end of the dog or lock-set 16 so as to move its upper end out of its recess, when said locking pin will fall into its locking position. In order to hold the locking pin on 100 the "half-lock", I form a recess 24^a in which the tail of the knuckle can fit so as to permit the pin to rest on it. It will also be observed that when the parts are in the positions shown in Fig. 1, not only does the spring 21 105 tend to force the locking pin down, but the weight of said pin and also of the long crank handle 47 has a similar tendency. 110

In the forms shown in Figs. 6, 7, 8 and 9, I construct the parts so that the vertically 115 moving pin locks the knuckle in position when said pin is elevated instead of when it is lowered. In these said figures, 50 designates the locking pin which is preferably of the form shown in Fig. 8, and has a groove or 120 channel 51 into which the wrist pin 52 works; this wrist pin formed on a crank-arm projecting from a rocking shaft, which may be identical with that shown in Figs. 1, 2 and 3. As before stated, in this form the locking pin 125 locks the tail of the knuckle in position when it is elevated as shown in Fig. 7, and when the rock-shaft and its parts are moved to lower the locking pin 50, the knuckle may be moved as said locking pin is then below the 130

level of the tail of the knuckle, as shown in Fig. 6. In this form, the dog or lock-set 54 is so shaped that its operative point 55 drops over the locking pin, when the latter is completely lowered, and holds the same down. When the knuckle is thrown out into its closed position in the act of coupling, its tail swings over the top of the locking pin and in the act of passing the pin, said tail swings 10 against the dog or lock-set 54 and pushes it to the rear, and the locking pin then is raised by the spring acting on the rock-shaft 56 until the locking pin rests against the tail of the knuckle, as shown in Fig. 6. The further inward movement of the tail of the knuckle causes it to swing past the locking pin, when the latter is elevated to the position shown in Fig. 7 and locks the knuckle in its coupled position.

20 I wish to call particular attention to the manner in which my locking pin works and is situated. Of course I do not intend to claim broadly a vertically operating pin, for these are old and are, in fact, shown in some of my prior patents; but I believe I am the first to provide a vertically operating pin of the character shown in my drawings, where the pin works in a housing which protects the pin from material falling over or into the coupler. In view of this, I do not wish to limit my claims to what is shown in my drawings, as I am merely showing what I now consider is the preferable embodiment of my coupler, but refer to the appended claims in which 35 the scope of my invention is clearly defined.

What I claim as new is:

1. In a car coupler and in combination with the swinging knuckle thereof, a vertical recess or opening having its upper end closed, 40 a vertically operating locking pin working in said vertical recess or opening, said pin snugly fitting said recess or opening and having no horizontal movement therein, the walls of said vertical recess or opening extending 45 above and below the center of said pin whereby the latter has a bearing on each side of the knuckle, the aforesaid vertical operating pin having an opening or groove in its lower end, a transverse bearing on the coupler, a rock 50 shaft transversely supported in said bearing, and an arm projecting from said rock shaft co-acting with the grooved lower end of said locking pin, substantially as described.

2. In a car coupler and in combination 55 with the swinging knuckle thereof, a vertical recess or opening having its upper end closed, a vertically operating locking pin working in said vertical recess or opening, said pin snugly fitting said recess or opening and having 60 no horizontal movement therein, the walls of said vertical recess or opening extending above and below the center of said pin whereby the latter has a bearing on each side of the knuckle, the aforesaid vertical operating pin having an opening or groove in

its lower end, a transverse bearing on the coupler, a rock shaft transversely supported in said bearing, and a crank or lever connected with the other end of the said rock shaft, substantially as described.

3. In a coupler and in combination with the swinging knuckle and its tail, a housing having a vertical opening therein, a vertically operating pin contained within said housing, said housing having an opening near its front 75 through which passes the tail of the knuckle and an opening at the rear, and a lock-set projecting through said opening at the rear of the housing, substantially as described.

4. In a coupler, a locking pin and means 80 for operating said locking pin from its lower end, said means comprising a rock-shaft, an arm projecting from said shaft and co-acting with said locking pin and a spring arranged to hold said parts in locking position, substantially as described.

5. In a coupler, the combination with a locking pin, of a rock-shaft suitably supported, an arm at one end of said rock-shaft having operative connection with said locking 90 pin and an operating handle or lever connected with the other end of said rock-shaft, and a spring for holding said parts so that the locking pin is in its locked position, substantially as described.

6. In a coupler, the combination with a vertically moving locking pin, a rock-shaft suitably supported and provided with an arm co-acting with the lower end of said vertically operating locking pin and a handle or lever 100 connected with the other end of said rock-shaft, and a spring for holding said rock-shaft in position, substantially as described.

7. In a coupler, a locking head having a vertical recess therein, a vertically operating 105 locking pin located within said recess, said recess having an opening in its front through which swings the tail of the knuckle and an opening in its back, and a lock-set projecting through the opening in the back of the housing, substantially as described.

8. In a coupler and in combination with the knuckle thereof, a vertical recess or opening having its upper end closed, a vertically 115 operating locking pin working in said recess and having a groove or recess in its lower end, and means co-acting with said grooved lower end for operating said pin, substantially as described.

9. In a coupler and in combination with the knuckle thereof, a locking pin having an opening or groove in its lower end, and a rock-shaft having an arm co-acting with said grooved lower end for operating said locking 125 pin, substantially as described.

10. In a coupler and in combination with the swinging knuckle thereof, a vertical recess or opening, and a vertically operating locking pin working in said recess or opening, said pin 130

locking said knuckle closed when in one position and releasing said knuckle when in its upper position, substantially as described.

11. In a coupler and in combination with 5 the swinging knuckle thereof, a vertical recess or opening having its upper end closed, and a vertically operating locking pin working in said recess or opening, said pin locking said knuckle closed when in one position and

releasing said knuckle when in its upper position, substantially as described. 10

Signed by me at Washington, D. C., this 16th day of Oct. 1903.

PERRY BROWN.
